PUMP

Charles R. Neeson, Dayton, Ohio, assignor, by
mesne assignments, to Chrysler Corporation,
Highland Park, Mich., a corporation of Del-
aware

Application June 26, 1937, Serial No. 150,590

2 Claims. (Cl. 103—126)

My present invention relates to a pump of general utility in many fields and of particular utility for circulating a lubricating medium through engines or machines of any type which may operate in reverse. A specialized machine of this type is a radial compressor such as more fully set forth in my copending applications, Serial Numbers 145,585, 145,586, 145,587, 145,588, and 145,589, filed on May 29, 1937, which comprises a sealed compressing unit for refrigerants including a motor and compressor sealed into a casing, a portion of which forms an enclosed oil reservoir. Within this oil reservoir there is mounted a pump for circulating oil through the unit to cool the motor and to lubricate the bearings and other working parts. As fully set forth in my aforementioned application, Serial Number 145,586, the motors of such units may operate in either direction, the direction of rotation depending entirely upon the manner in which the motor connections are connected to the power lines. Through carelessness or error the connections may be made so that the motor would rotate counter-clockwise whereas clockwise rotation would be desired, or even after the original connections had been made the lines may be reversed somewhere between the power plant and the motor with the same effect. The compressor of my design is capable of operating at maximum efficiencies regardless of the rotation of the motor to which it is connected, and as set forth in my application, Serial Number 145,586, I have combined therewith a pump having automatic reversing features so that in case a motor reversal occurs the pump will nevertheless continue to force a lubricant through the system in the proper direction. An object of the present invention is to devise a simple form of pump which will operate in such a combination, whether the same be the combination of a compressing unit and pump, or any other combination including a pump. A further object of the invention is to devise a pump which may be used in any desired location or with any driving mechanism so that careful selection of pump direction and motor direction characteristics is rendered unnecessary. A further object of my invention is to adapt the gear type of pump to uses requiring automatic reversing characteristics, thereby providing a more simple and cheaper form of pump than heretofore found available for such uses.

The object of my invention will be more fully apparent after consideration of the following specification taken in connection with the accom-

panying drawings wherein like numerals refer to like parts throughout.

Referring to the drawings, Fig. 1 is a plan view of one embodiment of my present invention; Fig. 2 is a vertical cross-section taken along line 2—2 of Fig. 1; Fig. 3 is a cross-section through the pump taken along line 3—3 of Fig. 2 and looking in the direction of the arrows; Fig. 4 is a plan view of the lower portion of the pump housing after all removable parts have been removed therefrom; Fig. 5 is a plan view of the upper portion of the pump housing, similar to Fig. 4, showing the flow-reversing member in position and showing in dotted outline the pump parts rotating in a clockwise direction; and Fig. 6 is a view similar to Fig. 5 showing the pump parts rotating in a counter-clockwise direction.

Fig. 1 discloses a pump housing 10 having bolted to the top thereof a pump head 11 which is provided with a journal 12 having bearings 13 and 14 within which rotates a driving shaft 15 connected to a motor, line-shaft or other driving means. The shaft 15, as more clearly seen in Figs. 2 and 3 is fastened to a driving gear 16 having peripheral teeth which is preferably shrunk-fit onto the end of the shaft, which gear 16 is eccentrically located with respect to an outer ring gear 17 having internal teeth of the same shape but greater in number by one tooth so that the gear teeth are in mesh at one point only and are exactly disengaged at a diametrically opposite point. Such gear pumps are well-known and the contours of the gear teeth assume several forms, the principle of the pumps being that at one side the teeth separate thereby causing fluid to be drawn into the space between the gears, and at the other side the teeth come together thereby causing fluid to be forced from the spaces between the gears. The ring gear 17 is of the same thickness as the gear 16 and the two are placed within a bearing depression in the lower surface of the pump head 11.

A reversing member 18 is mounted in the pump housing 10, the reversing member having the same diameter and being concentric with the ring gear 17. The member rests upon a shoulder 19 and is rotatively guided by a bearing extension 20 slidably mounted in a socket 21. The extension 20 is hollow and a spring 22 and thrust ball 23 mounted therein force the upper face of the reversing member 18 against the lower faces of the gears. The upper face of member 18 is provided with channels 25 and 26, each channel extending inwardly from the edge of the member a short distance and then substantially concentrically

about the member for approximately 170° , thereby forming a central island 27 surrounded by the grooves 25 and 26 except for narrow raised strips 180° apart at one side of the entrances to the channels 25 and 26. The channels are of such a width and so located as substantially to underlie the gear teeth and pockets between the gear teeth at all times.

The pump housing 10 is recessed to form channels 28 and 29 of substantially the same depth as channels 25 and 26, each channel extending from a diametrically opposite point approximately 170° about the inner circumference of the housing, thereby providing lands 30 and 31 spaced 180° apart. The relationship of the channels in the pump housing to the reversing member is such that, with the reversing member in the position shown in Fig. 5, channel 25 is in communication with channel 28 adjacent land 31; and when the reversing member is in the position shown in Fig. 6, channel 25 is still in communication with channel 28 but this time adjacent land 30. Channel 28 forms an extended suction port leading from the opening 32 which communicates with a suction pipe 33; and channel 29, forms a discharge port communicating with the discharge opening 34 which leads to the discharge pipe 35. When shaft 15 is rotating clockwise as shown in Fig. 5 the friction between the faces of the gears and the reversing member causes the reversing member to assume the position shown, whereas if the shaft 15 reverses direction the friction between the faces causes the reversing member to assume the position shown in Fig. 6. In Fig. 5 the gear teeth are separating adjacent channel 25, the open end of which is directly opposite opening 32, so that fluid entering channel 28 flows directly into channel 25 and thence into the enlarging spaces between the gear teeth. As soon as the gear teeth have passed beyond the channel 25 and approach the closed end of channel 26 the pockets between them begin to decrease in size thereby forcing fluid into the channel 26, the open end of which is directly opposite the discharge opening 34. In Fig. 6 fluid emerging from opening 32 traverses the length of channel 28 and channel 25 into the increasing pockets, then is forced into the channel 26 by the decreasing pockets, traverses the length of channel 29 and is discharged through opening 34.

In order to limit the reversing movement of the reversing member so as to have channel 25 always in communication with channel 28, and channel 26 with channel 29, the pump housing is provided with a recess 40 provided with a raised portion 41 forming abutments 42 and 43 spaced approximately 180° apart. The reversing member is provided with a lug 44 of such width as to limit the movement of the reversing member to approximately 170° upon striking abutments 42 or 43 in the course of being turned due to the frictional contact of the faces of the gears and the reversing member.

In order that trapped fluid in recess 40 may not prevent the reversing member from becoming properly seated on shoulder 18, a relief opening 50 may be provided through the reversing member in the discharge or high-pressure side of the pump. By placing relief opening 50 in the high-pressure side of the pump the pressures on opposite surfaces of the reversing member are placed substantially in equilibrium or greater on the lower surface, thereby making certain that the faces of the gears and the reversing member are kept in contact. Were it not for this feature

the reversing member might be lowered against the shoulder 18 as soon as pressure built up to a greater extent than the strength of the spring 22, thus permitting some fluid to bypass from the discharge side back to the suction side. 5

Having described a preferred form of my invention it should be apparent to those skilled in the art that the same may assume several modifications in arrangement and detail, all such as come within the scope of the following claims 10 being considered a part of my invention.

I claim:

1. An automatically reversible, uni-directional pump comprising a housing having an extended suction port and an extended discharge port 15 therein, said ports each extending through an arc of slightly less than 180° in the internal wall of said housing, a driving gear and a driven ring gear mounted within said housing, said driving gear having a flat face and peripheral teeth and 20 said ring gear having a flat face in the same plane as the flat face of said driving gear and internal teeth in full engagement with said peripheral teeth at one point only, said driving gear having one less tooth than the number of teeth on said 25 ring gear and said flat faces lying in a plane above the plane of said extended ports, and a rotatably mounted reversing member lying in the plane of said extended ports and having a flat face held in frictional engagement with the flat 30 faces of said gears, said reversing member being provided with means to limit rotation thereof to substantially 180° and being provided with two open channels extending into the member from the flat face thereof and lying opposite and in 35 communication with the pockets between the teeth of said gears, each of said channels being provided with a restricted opening extending to the edge of said member, one of said channels being in communication with said suction port and the 40 other of said channels in communication with said discharge port at all times regardless of the position of said reversing member, said reversing member being frictionally rotatable by engagement with said gears from one extreme position 45 to another extreme position in accordance with the direction of rotation of said gears whereby to maintain uni-directional flow through said pump regardless of the direction of rotation of said gears. 50

2. An automatically reversible, uni-directional pump comprising a housing having an extended suction port and an extended discharge port 55 therein, said ports each extending through an arc of slightly less than 180° in the internal wall of said housing, a driving gear and a driven ring gear mounted within said housing, said driving gear having a flat face and peripheral teeth and said ring gear having a flat face in the same plane as the flat face of said driving gear and internal 60 teeth in full engagement with said peripheral teeth at one point only, said driving gear having one less tooth than the number of teeth on said ring gear and said flat faces lying in a plane above the plane of said extended ports, a rotatably 65 mounted reversing member lying in the plane of said extended ports and having a flat face held in frictional engagement with the flat faces of said gears, and resilient means normally forcing said flat face of said reversing member into frictional engagement with said flat faces of said gears, said reversing member being provided with means to limit rotation thereof to substantially 70 180° and being provided with two open channels extending into the member from the flat face 75

thereof and lying opposite and in communication with the pockets between the teeth of said gears, each of said channels being provided with a restricted opening extending to the edge of said member, one of said channels being in communication with said suction port and the other of said channels in communication with said discharge port at all times regardless of the position

of said reversing member, said reversing member being frictionally rotatable by engagement with said gears from one extreme position to another extreme position in accordance with the direction of rotation of said gears whereby to maintain 5 uni-directional flow through said pump regardless of the direction of rotation of said gears.

CHARLES R. NEESON.
